2,183,143

METHOD OF PREPARING COLOR-PRINTING PLATES

Walter S. Marx, Jr., Port Washington, N. Y., assignor to Printing Arts Research Laboratories, Inc., a corporation of Delaware

Application September 27, 1934, Serial No. 745,682

2 Claims. (Cl. 95—5.1)

My invention relates to a new and improved method of preparing color-printing plates. While the invention relates particularly to the preparation of multi-color printing plates, certain aspects of the invention apply to plates for line-printing in black, and for color printing in half-tone.

One of the objects of my invention is to provide a new and improved method of preparing plates for printing cartoons or color comic supplements in multi-color, so as to provide a simple and efficient method for newspaper work.

Another object of my invention is to provide a new and improved method of preparing plates for printing in multi-color, so as to eliminate the necessity of using skilled operators for securing correct color rendering and blending.

Other objects of my invention will be set forth in the following description and drawings which illustrate certain preferred embodiments, it being understood that the above statement of the objects of my invention is intended to generally explain the same without limiting it in any manner.

Fig. 1 represents the master black-and-white drawing which is made originally by the artist, or a line positive thereof, and having outline areas S. The line positive may be made on transparent Celluloid, or other transparent material, if desired.

Fig. 2 represents a photographic or other reproduction of the subject matter to be reproduced, on a sheet of light-permeable or translucent or transparent material. The reproduction represented in Fig. 2 has been shaded by hand, so as to reproduce all the colors to be printed with the exception of black.

Fig. 3 is a positive corresponding to one of the colors in the colored cartoon or the like, which is to be reproduced. This figure has been made by preparing a plate which prints one of said colors, (such as red, for example), and printing with said plate and with a black ink. Hence Fig. 3 represents the red portions (for example) of the cartoon or the like.

Fig. 4 represents a different color of the cartoon or the like. For example, Fig. 4 can represent the blue color.

Fig. 5 is a positive corresponding to the remaining color of the cartoon or the like, such as yellow. When the plates corresponding to Figs. 3, 4 and 5 are inked with suitable colored inks, and such plates are used in multi-color printing, together with a key plate for printing

the black lines or areas shown in Fig. 1, the subject matter is reproduced in full color.

Fig. 6 illustrates certain apparatus which is used in carrying out the improved method.

Fig. 7 illustrates the finished printed result, 5 printed with the color plates, and with the key plates for printing black lines or black areas.

Fig. 8 is an enlargement of a portion of Fig. 6, showing the arrangement of the halftone screen and the other associated apparatus. 10

Fig. 9 illustrates the apparatus used for preparing a transparent color scheme, and which is also used for opaquing certain portions of the negatives which it is not desired to print.

In ordinary multi-color printing, printing 15 plates are prepared, each said plate corresponding to its respective color. In ordinary color printing the printing plates are all half-tone plates, and each of said plates is photographically printed from a suitable negative or the like. 20

In preparing said negatives, reflected light has been used, and said light has been caused to pass through a half-tone screen located in the ordinary type of photo-engraving camera, between the lens and the sensitized plate. 25

In preparing colored cartoons or comic supplements, a variation of this method has been used. In this variation a plate is used for printing the black areas and said plate is a line plate, instead of being a half-tone plate. 30

The usual method of preparing color plates for printing colored cartoons or comic supplements is by means of the so-called "Benday" process.

According to the "Benday" process, line prints 35 are made upon the metal printing plates, by using the line negative which has been used in preparing the plate for printing the black-and-white tones. Such plates are then stippled by the operator with the use of a "Benday" screen, in order to produce half-tone areas which correspond to the colors or to the color combinations which are to be used. 40

In carrying out this process, the operator works from a color sketch, and the correctness of the 45 rendition and the blending of the colors depends upon the individual skill of the operator.

Furthermore, a complicated process is required in order to render the stippling resistant to acid, so that the processes heretofore known require 50 considerable time and many errors can occur.

Even if a skilled operator uses the "Benday" process, many color values cannot be secured properly. For example, areas such as the representation of the sky are usually reproduced by 55

means of the "Benday" process, with half-tone dots of the same size, thus producing a flat and unnatural color effect.

5 My invention utilizes the advantages of color separation by filtration, which is an improvement over the manual separation necessary with the "Benday" process.

10 The ordinary multi-color printing process is not used for printing colored comic supplements or colored cartoons on high-speed newspaper presses, because it is desired to have a solid black line for outlining the objects, the lettered matter and the like.

15 While my invention relates particularly to the printing of colored cartoons, colored supplements and the like, by means of high speed rotary newspaper presses, it is also applicable to the well known color printing processes, using two colors, three colors, and four or more colors, and fine 20 screen reproduction.

25 In the preparation of colored comic supplements according to my invention, a black and white line positive (not half-tone) may be prepared by suitable photographic printing of the original line drawing of the artist without the use of a screen. This black-and-white line positive is represented in Fig. 1.

30 The color printing plates desired can be prepared according to several methods.

First method

35 A sheet of light-permeable material, such as translucent tracing cloth or paper or the like, is now stretched in contact with and over the drawing or positive which is represented in Fig. 1. This tracing paper is sufficiently light-permeable so as to render the underneath drawing visible in full detail, when the sheet of tracing paper is in actual contact with the original drawings or the like. If desired, said tracing paper may be relatively light-impermeable, so that it requires actual contact with the drawing, in order to render the black lines visible. However, the tracing material may be of any desired degree of transparency.

The operator then applies coloring material to this tracing paper or the like, so as to reproduce the desired color scheme, in all the colors thereof. If desired, the artist can paint the colors upon the tracing cloth or paper, using any suitable paints or coloring matter. These paints are preferably opaque.

60 The colored sheet of tracing material which is thus secured, is represented in Fig. 2. This tracing paper does not carry the black lines or black areas and it merely has patches of color which are located in areas corresponding to the color areas between the black lines or black areas of the original drawing.

If the colored sheet of tracing material which has been thus secured is viewed by reflected light, the colored areas are clearly visible.

65 A series of light-permeable and continuous-tone separation negatives (not half-tone negatives) are prepared from the colored positive which is shown in Fig. 2. Each said negative is prepared by illuminating the colored positive which is shown in Fig. 2 by means of reflected light, and successively interposing the usual color 70 separation filters between said colored positive and the respective sheets of sensitized material. Each said separation negative can be made on transparent Celluloid or transparent glass, and it corresponds to one of the primary colors of said hand-colored positive.

A half-tone or screen positive is prepared from each said negative. Each half-tone positive can be produced by means of transmitted light, by means of the apparatus shown in Fig. 6 and Fig. 8. The sheet of sensitized paper, transparent 5 glass, film, etc. on which the half-tone positive is made, can be located at the place occupied by member 7, a half-tone screen 4 is supported above the sensitized material by bars 5, and the negative is located at the place occupied by member 3. Light is sent through the negative by lamp L. This method of preparing a half-tone positive from a continuous tone negative is explained in my U. S. Patent No. 2,048,876, dated July 28, 1936.

10 In preparing the respective half-tone positives from the respective continuous-tone negatives, the screen is turned in a horizontal plane so that the lines are at different angles at each exposure, as it is customary in half-tone multi- 15 color work.

20 The half-tone positives which are thus produced, can be used in preparing corresponding half-tone negatives, by contact printing or by photographic copying and said negatives are used 25 in preparing half-tone printing plates for printing the various colors. These half-tone printing plates, made of metal or the like, together with a black line "key" plate for printing the black areas or black lines, will reproduce the cartoons 30 or supplements in color, and with the black lines or black areas of the original.

Second method

35 A full positive color transparency, such as an autochrome transparency on transparent glass or transparent Celluloid film, is made from the member shown in Fig. 2, which is prepared as in the first method as above described. In said autochrome transparency, the colors are transparent, instead of being opaque. This transparency is subjected to three exposures, each exposure being made with a different filter of a three-color filter set. The filters of this set ordinarily consist of an orange filter, a green 45 filter and a blue filter.

40 The autochrome which is utilized is a positive, and half-tone or screen negatives are made therefrom.

45 In making these half-tone negatives, I can use the apparatus shown in Fig. 6 and Fig. 8. If the autochrome is of the same size as the desired matter to be printed, it can be located between the screen 4 and the sensitized glass or other material upon which the negatives are to be made. Under such circumstances the colored surface 6e of the autochrome 6 may be in contact with the emulsion or sensitized surface 7e of the transparent plate 7 on which each negative is to be made, and the screen is supported a short 50 distance above the autochrome by bars 5. However, said autochrome 6 may be reversed in position, if desired, since the autochrome is thin. This may be done if it is desired to reverse an image from left to right. The filter is located 55 preferably adjacent to, and above or below the lens in making each exposure. The filter may be located in any position in front of the emulsion 7e.

60 If the autochrome is of a different size than the desired result, it can be located in the negative carrier indicated by the member 3 shown in Fig. 6, so that the autochrome is focused by the lens upon the sheets of sensitized material 7, upon which the negatives are to be made. The 65 70 75

filter can be located at any suitable place between the light and the material on which the negatives are to be made.

The three half-tone negatives which are thus secured, can be used for printing directly upon the sensitized surface of the sheets of metal which are to be etched for making the printing plates.

Third method

Instead of using opaque colors upon the light-permeable tracing member which is placed above the drawing or positive to be reproduced, I can use transparent colors, which are applied by hand on a member made of transparent material, such as glass or Celluloid or the like, which is placed over the drawing or positive which is depicted in Fig. 1. That is, instead of of using the relatively translucent tracing paper previously mentioned, I use a transparent material such as glass or Celluloid, and I use transparent colors instead of opaque paints. The apparatus for performing this operation is shown in Fig. 9. This shows a sheet of white paper 30, which is illuminated so as to reflect white light. An easel having triangular vertical walls 31 and a bar 32, may be used for supporting the original drawing or positive, and the superposed and contacting transparent sheet.

The result is to produce a hand colored transparency 6 which is shown in Fig. 6 and Fig. 8 of the drawings herein. This transparency is of the type shown in Fig. 2, in that there are no blacks represented thereon.

As shown in Fig. 6 and Fig. 8 of the drawings herein, the transparency 6 may be placed in contact with its colored side 6e contacting with the emulsion surface 7e of a transparent member 7 made of glass, Celluloid, etc. As previously stated, the transparency 6 may be reversed in position.

The half-tone screen 4 is held suitably spaced from the member 6, by means of bars 5. The projector is provided with the usual lamp L and with the lens holder 2.

A filter 3 is interposed between the lamp L and the lens of the projector, or in any position in front of the sensitized emulsion. A suitable set of these colored filters is used for producing the required color separation negatives.

In order to secure a negative which corresponds to the blue color, an orange light is used, by using a filter having an orange color. In order to secure a negative corresponding to the red color, a green light is used, by using a filter having a green color. In order to secure a negative corresponding to the yellow color, I use a filter having a purple color or a blue-violet color. These colors are selected as being complementary to the colors of the primary colors of the printing inks used in the final reproduction of the work.

The projector is provided with a suitable adjustable aperture stop, in order to control the sizes of the half-tone dots, which are formed upon the screen or half-tone negatives. Of course individual sheets of sensitized material 7 are used for producing the individual negatives corresponding to the primary colors. The half-tone negatives thus secured are utilized for printing upon the sensitized surfaces of metal plates which are used for making the printing plates. When these printing plates are inked with colors having the necessary relationship to the colors used in the filtering of their respective negatives,

said plates will reproduce the original color pattern. Of course an additional key plate is used for reproducing the black lines of the original drawing. This finished result is shown in Fig. 7.

It will be noted that if Fig. 1 represents a line positive of the original drawing, said line positive is made from a negative of said original drawing, which negative has been made according to the scale to be reproduced. Hence there is no enlargement in doing the screen work illustrated in Figs. 6 and 8.

In order to prepare the key plate, which is to be used for printing in black over printings of the three previously described half-tone plates, said negative of the original drawing is used for photographically printing upon the sensitized surface of the sheet of metal from which the metal printing plate is made, to be used as a black key plate for use with the color plates.

If desired, the black-and-white negative which is to be used for making the black key printing plate, may be made by making a contact print on transparent material from the positive, which was used in making the colored transparency. All this photographic printing work is done by actual contact so that errors which may arise from improper registration and focusing, are absolutely eliminated.

Fourth method

This method differs from the third method as follows:

A black-and-white positive is printed lightly upon the transparent sheet of film or glass upon which the color scheme is to be prepared. For this purpose, the sheet of film or sheet of glass 6, is provided with a sensitized emulsion 6e in the usual manner. The opaque portions of the black and white positive which are printed upon this transparency have a silver density of about forty per cent of the total possible deposit, although this proportion can be varied. In the other methods, the black lines have not been reproduced, either upon the sheet of tracing paper or upon the transparency, but in this method I do reproduce said black lines, preferably fainter than in the original. This black-and-white positive which has been thus directly applied to the transparent sheet of film, glass, or the like which is to be colored, is used as a guide for applying the color or colors.

Separation negatives are then made from this color transparency according to the third method. Each separation negative then carries the lightly-printed black part of the original in screen or half-tone dot formation. This lightly-printed key image is advantageous since definite guide lines are thus incorporated in the color separation negatives. This facilitates the blocking out of undesired portions of each negative, by the application of opaque color to any desired portion of each said negative. For example and in Fig. 5, there are large areas which are free from yellow color, and such areas are blocked out of the negative from which the printing plate is prepared.

Likewise color separation filters are never completely efficient, so that an effect which is due to one color, or any superfluous image, may be blocked out by the application of opaque color. Likewise other circumstances may make it desirable to apply opaque color to any desired portion of the negative, so as to make corrections of the like.

All this work is facilitated by means of the

lightly printed key image in black and white. The purpose of printing the black lines more lightly than in the original is to make it possible to form a screen or half-tone dot formation of these lines in the screen negative, instead of transparent or clear lines, in said negative.

Since these guide lines are screen or half-tone lines, instead of being continuous-tone and heavy lines, the effect of these lines upon the 10 final color proof is negligible, since said guide lines are printed in dots of the same color as the respective color plate.

When the four plates print in accurate registration, the key plate prints in black color directly over the screen or half-tone dot lines printed by the color plates, so that said screen lines are entirely eliminated.

The relatively light printing of the black lines of the original image is secured by suitable short 20 exposure and by a suitably short period of development.

For reasons above mentioned, I consider that the fourth method is the preferred embodiment, particularly where colored supplements to news- 25 papers are to be printed.

It will be noted that the fourth method differs from the third method in that a light black or grey image is retained in the color transparency. It is obvious that this same variation may be applied to the photographing of the color scheme of the first and second methods if desired, in order to achieve similar results.

According to the second, third and fourth methods I secure three color separation negatives, 35 each of which is full size and half-tone. These negatives together with the black-and-white key negative are used for preparing the four printing plates in the usual manner.

According to the first method, the screen or 40 half-tone separations and the black and white key plate are positives, and contact negatives or reversals are made from these positives and such negatives are used in the usual manner to make the printing plates.

45 In order to eliminate undesired color relations or color combinations, due to the fact that even the most efficient color-separation filters are not sufficiently monochromatic, it is desirable to "opaque" those portions of the negatives which 50 are not desired, before the printing plates are made. This opaques operation may be performed by the use of the apparatus shown in Fig. 9, by mounting a sheet of ground glass 33 upon the easel, and placing the transparency 6 upon 55 said sheet of ground glass.

According to my invention, the artist can work on a single sheet with media which can be handled easily. Likewise and by using the third and fourth methods, I can use transmitted light for 60 color separation having nearly pure color characteristics, which passes through the colored transparency. I can thus obtain a longer scale of tone rendition than if the image is projected through a photographic negative which has silver grains in its emulsion, and thus, according to 65 my improved method, I can utilize the entire color spectrum for color gradation. This is not possible when separation negatives are made by the use of reflected light.

70 In newspaper work, a coarse screen is used, but fine screens may be utilized and the invention can be utilized for any kind of reproduction in colors.

While I have described the use of three color

plates, I can use color plates corresponding to any desired range or separation of the colors.

Generally speaking, I produce the desired color scheme upon a sheet of light permeable material, which is preferably in contact with the representation of the black and white matter which is to be reproduced in color. This sheet of light-permeable material may be translucent or transparent and the color scheme may be made with the use of opaque coloring matter, or with the 10 use of transparent coloring matter.

Said sheet of light-permeable material may have the black and white lines, or said black and white lines may be omitted, according to the respective embodiment which is utilized. This 15 sheet of colored and light-permeable material is now used for making what may be designated as separations.

In the first method which has been described, the separations are continuous-tone negatives. 20

According to the second method, the color transparency may be considered as corresponding to the transparent member which is used in the third method.

Hence, according to the second method, half- 25 tone negative separations are produced, whereas according to the first method the negative separations which are initially prepared from the sheet of translucent tracing paper are continuous-tone. For this reason the second method is 30 superior to the first method because the first method requires photographic reversal or an additional photographic printing.

According to the third and fourth methods, a 35 transparency is directly produced so that the preparation of the autochrome transparency is unnecessary. According to the third and fourth methods half-tone negative separations can be made directly from the original color transparency.

Where in the claims I have specified that the transparency which bears the color scheme, is maintained in substantial contact with the sheet of material on which the half-tone separation 40 is produced, I do not wish to limit myself to actual contact, as it is sufficient for the purposes of my invention if focussing through lenses is rendered unnecessary.

I have shown preferred embodiments of my 45 invention, but it is clear that numerous changes and omissions can be made without departing from its spirit. For example, the invention is not limited to the use of a solid unscreened black key plate, but may utilize a series of half-tone plates alone, or combination line and half-tone plates, 50 of any desired color range prepared in accordance with the principles here disclosed.

Whenever I have referred to the use of an autochrome, it is to be understood that I can use any type of transparency which is made 55 photographically. Likewise, I can use a half-tone plate for printing black lines, black colored areas, or black tones in the picture. For example, when it is desired to duplicate an oil painting which has been made on opaque material, said painting may 60 have black areas of substantial size. I would then prepare a colored transparency of said picture to the desired scale, including (if desired) the black lines or black areas thereof, and I would use 65 said transparency by causing it to contact with the emulsion side of the transparent plate on which the half-tone negative is to be prepared. I have referred repeatedly to black lines or black areas and it is to be understood that whenever 70 I refer to black lines in the claims, this term 75

includes black areas or black sections or black portions. The white light is sent through the half-tone screen and through the transparency, a filter being suitably interposed, and the filtered light which has passed through the transparency is caused to affect the emulsion on the plate. Color separations are thus made, and a fourth exposure through a yellow or correcting filter can be made, in order to prepare (by the fourth exposure) a half-tone plate for printing black lines or black areas in half-tone.

In some cases, the artist may supply a color transparency, made with transparent colors. This transparency can be used by contacting it with the emulsion side of the transparent plate or film on which the half-tone negative is to be made, the white light being caused first to pass through a screen and through a filter.

I do not wish to be limited to any particular positions of the filter and of the screen relative to the sensitized plate or film on which the half-tone negative is to be made.

For example, the white light can first pass through the filter, then through the screen, then through the transparency, and then fall upon the emulsion of the plate. The light may be caused to pass first through the screen, then through the filter, and then through the transparency. The light can also first pass through the screen, then through the transparency, and then through the filter. A thin filter such as a gelatine filter can be used in the last mentioned combination, and said filter can be caused to contact with the emulsion of the plate or film, and the transparency can contact with the filter.

The transparency can be located in the projector, so that it is focused upon the plate or film. In the last mentioned case, the filter can be above or below the transparency and above the lens, or the filter can be below the lens, and located between the lens and the screen, said screen being above the plate or film.

Heretofore, and in order to produce plates for multi-color printing, the original colored painting or the like was made with opaque paint on opaque material, which opaque material, such as canvas, usually had a white color. Said painting was then illuminated so that light was reflected therefrom, and this reflected light was used with a series of filters and with a screen, so as to produce direct half-tone negatives by reflected light. This led to complications and errors. The color of the opaque background material and the grain of said material affected the color separation. Likewise, the operator had to adjust the various factors simultaneously in order to secure simultaneous color separation by reflected light and screen dot formation.

According to my invention, if I desire to re-produce a painting which is made with opaque

paint, I first use reflected light to produce continuous tone separation negatives, according to the final scale of the reproduction. These continuous tone negatives are then used to make half-tone positives, thus dividing the work into two stages. Likewise, the scale of the work remains unchanged during the half-tone work.

It is far superior to prepare a transparency of the painting, so that transmitted light can be used for making half-tone separation negatives directly from the transparency, and this is the preferred method. This transparency is made according to the desired scale, so that the half-tone work and color separation are done by contact printing, without any change in scale.

This is very important in securing plates which will produce color printing in proper registration.

The function of the half-tone screen is to interrupt the beam of transmitted light, at predetermined portions of said beam of light. Said interrupted beam of light passes through the transparency and it is filtered at any suitable point in advance of the sensitized surface on which the half-tone separation is being prepared. By having the transparency either in actual contact with, or in substantial contact with said sensitized surface (as where a filter is interposed between the transparency and the sensitized surface) the half-tone separation is made without any change in scale and without the need of focusing.

I claim:

1. In the art of preparing printing plates for multi-color printing of matter, said matter containing black lines, those steps which consist in photographically printing a black and white positive of said matter on a sheet of transparent material while photographically printing the black lines on said positive more lightly than the black lines in the original matter, and representing the color scheme with the exception of black color, upon said sheet.

2. In the art of preparing printing plates for multi-color printing of matter, said matter including black lines, those steps which consist in photographically printing a black and white positive of said matter upon a sheet of transparent material while photographically printing black lines on said positive more lightly than the black lines on the original, preparing the color scheme, with the exception of black color, upon said sheet of transparent material, preparing separation half-tone negatives from said colored sheet of transparent material, blocking out undesired portions of said negatives, said negatives having the black lines which are on said sheet of transparent material represented in half-tone dot formation, and then using said negatives for preparing printing plates corresponding to the respective colors.

WALTER S. MARX, JR.
